UNITED STATES PATENT OFFICE

169,265

CANDY BAG

John Lavezzorio, Chicago, Ill.

Application November 14, 1952, Serial No. 22,281

Term of patent 14 years

(Cl. D58—2)

To all whom it may concern:

Be it known that I, John Lavezzorio, a citizen of the United States, residing at Chicago, in the county of Cook and State of Illinois, have invented a new, original, and ornamental Design for a Candy Bag, of which the following is a specification, reference being had to the accompanying drawing, forming part thereof.

Fig. 1 is a front elevational view of a candy bag, showing my new design;

Fig. 2 is a fragmentary top edge view; and

Fig. 3 is a rear elevational view.

I claim:

The ornamental design for a candy bag, as shown.

JOHN LAVEZZORIO.
